UNITED STATES PATENT OFFICE.

WILLIAM JAMES SCOTT, OF WASHINGTON, DISTRICT OF COLUMBIA.

TONE-CLARIFYING INSTRUMENT FOR USE IN COMMUNICATION.

Application filed January 29, 1921. Serial No. 440,995.

My invention relates to tone clarifying and interference eliminating means and has for an object thereof to provide an instrument which is selective in its action and which will eliminate the usual aeroplane noises but which will carry the voice, thus making speech possible between two or more persons in the same aeroplane, or between persons in different aeroplanes when used in connection with wireless telephony, telegraphy and the like.

While I will describe my invention as applied to aircraft it will be apparent that it is of much more general application and is adapted to use wherever inter-communication is desired in the presence of heavy interference.

With the above general objects in view and others which will be obvious to those skilled in the art from the description hereinafter, my invention consists in the features, details of construction and combination of parts which will first be described in connection with the accompanying drawings and then particularly defined in the claims.

In the drawings:

Figure 1 is a longitudinal vertical sectional view of one form of my instrument.

Figure 2 is an elevation of the complete instrument.

Figure 3 is a transverse vertical sectional view taken on line A—A of Figure 1, on an enlarged scale.

Figure 4 is a transverse vertical sectional view taken on line B—B of Figure 1.

Figure 5 is a detail view showing a modified construction of means for attaching branch leads to the sound transmitting chamber.

Figure 6 is a vertical sectional view of a modified construction of my instrument, parts being shown in perspective, and

Figure 7 is a vertical sectional view of a further modification, parts thereof being shown in perspective.

With particular reference to Figures 1, 2, 3 and 4, numeral 1 refers to a cylindrical shaped body which is made of a resonant

metal such as brass. Connected to and communicating with the interior of the cylindrical body are voice tubes 2, 2.

The space 3 into which the voice tubes lead may be termed the sound receiving resonating and reverberatory chamber and communicating therewith is a series of sound conveying tubes 4. These small tubes 4 break up or select the sound waves. Each series of selecting tubes connects through tubing having easy uniform curves, with the main leads 5, which in turn communicate with the tubing 6, where the voice waves are reunited in a clarified and amplified condition. The chamber formed by the tubing 6 may be termed the sound transmitting chamber or expansion, and as shown it consists of a stationary central portion 6* from which the receiver tubes 7, 7, lead, and end portions which are telescopically received within the central fixed portion. The purpose of this construction is to permit longitudinal adjustment of the selecting tubes and their connecting parts and the capacity of the receiving or reverberatory chamber in accordance with the pitch of the waves received. Any suitable mechanism may be provided for simultaneously moving the right and left hand series of selecting tubes like distances in opposite directions. By way of illustration, I show a lever 8 pivotally mounted at 9 and slidably connecting with a shank 10 attached to the right hand series of selecting tubes. The pivot 9 is so located that the same amount of movement given to shank 10 is transmitted through connecting rod 11 to shank 12 attached to the left hand series of selecting tubes. Ordinary means are shown for holding the lever 8 in adjusted position and it is thought that a description thereof is unnecessary.

Detachably connected with the voice tubes and receiving tubes are the flexible tubes 13 and 14 respectively, which are preferably sound proof. Any preferred form of helmet 15 may be attached to the receiving tubes.

If desired, microphones 16, 16, may be inserted in the sound transmitting chamber, and for the purpose of wireless telephone

communication in connection with the use of apparatus, a loud-speaker 17 may be inserted in the sound receiving chamber.

The ends of the small selecting tubes 4 are mounted in flanged plates 18, 18, while the main leads 5 are also mounted in flanged plates 19, 19.

It will be understood, of course, that the selecting tubes 4, leads 5, plates 18 and 19, 10 and tube 6, all move as one element when the size of the sound receiving chamber is adjusted for varying pitch.

In order that the various elements may be removed from the cylindrical body 1, it is 15 preferable to have the end walls thereof 20, 20, detachably mounted, as shown.

In operation for inter-communication between persons on the same aircraft, and assuming the speaker is at the right (Fig. 1), 20 then the path of the waves will be as shown by the arrows. The sound travels through tube 2 to the sound receiving chamber where it is broken up and passes to the right and left through the small selecting tubes 4 and 25 is reunited in the sound transmitting chamber, from which it passes to the right and left through the receiving tubes 7, 7, the speaker hearing his voice as well as the listener. In the passage through the selecting 30 tubes 4, sound waves other than those of the voice are so broken up that they apparently die away, so that when the waves are reunited in chamber 6 substantially only the voice waves remain.

To adjust the instrument for different 35 pitches it is only necessary to move the lever 8, thereby moving the two sets of selecting tubes and their connecting parts to increase or decrease the size of the sound receiving chamber.

For use in connection with wireless telephone or telegraph communication it is only necessary to insert the loud speaker in the sound receiving chamber and the operation 45 of my clarifying device or interference eliminator will be the same as that previously described.

With reference to Figure 5, the construction is the same as that disclosed in Figure 1 50 except that I provide a detachable connection between the tube 6 and the main leads 5. For this purpose the leads 5 are beaded as shown at 21, the ends of the leads being received in suitable apertures in a plate 22. 55 The operating shank 10 is provided with a shoulder 22' which abuts a suitably shaped plate 23 engaging the curved portions of main leads 5. The shank 10 screws into the plate 22 whereby the leads 5 are securely 60 held in position. In this construction the microphone may be screwed onto the end of the shank 10 or otherwise secured in place.

The construction shown in Figure 6 is somewhat similar to that already described, 65 though in this case only one set of selecting

tubes 4 is used, and I provide no means for adjusting the size of the sound receiving chamber 3. The passage of the sound waves in this case is, however, quite different. Here the waves after being broken up in selecting 70 tubes 4 pass through suitable tubes 24 and are reunited in the chamber 25, passing upwardly through this chamber the waves strike the deflector 26 and are deflected downwardly thereby into the tube 27 which 75 gradually tapers to the point 28 where it divides into the two receiving tubes 7, 7. The gradual taper is continued in the receiving tubes to the point where the flexible hosing is attached.

With reference to the further modification shown in Figure 7, the speaking tubes 2, 2, communicate with the selecting tube receiving chamber 3 as before described. In this case, however, alternate sets of selecting 80 tubes 4 communicate directly with the selecting tube transmitting chamber 28, near the bottom thereof, as shown at 29, while the other alternate sets of selecting tubes communicate with the sound transmitting chamber at a point relatively remote from the bottom of said chamber and by means of a series of small tubes 30, for a purpose to be described hereinafter.

The sound transmitting chamber is formed 85 by two telescopically arranged tubes 31 and 32, the former being stationary. Connected to the movable portion 32 is a screw threaded rod 33, which receives an adjusting nut 34 at its upper end whereby the tube 32, the selecting tubes 4, and the plates 35 and 36 supporting the selecting tubes, may be moved longitudinally to adjust the size of the sound receiving chamber 3.

All of the selecting tubes are in communication with the sound transmitting chamber 28 in the position shown in Figure 7, but if the tube 32 is given sufficient longitudinal movement the tube 30 will be cut out from communication with the sound transmitting 100 chamber, as the ports of these tubes will be covered by the tube 31. It is thus possible to cut out all of the tubes 30, but the construction is such that alternate sets of selecting tubes will always be in communication 105 with the sound transmitting chamber by way of the ports 29.

It should be explained that the reference hereinabove to the use of a microphone in the sound transmitting chamber forming an 110 element of the sound conveyor (which latter includes the complete sound conducting and more or less extended and circuitous passage leading initially from the sound receiving or reverberatory chamber) contemplates its employment as a transmitter in connection with suitable conventional or approved means, such as wire conductors leading to a receiver, and serving as a preferred or auxiliary means of taking the message. The micro- 115 120 125 130

phone construction may be of any approved type.

Moreover, while reference is above made to a so-called "breaking up" of the sound waves and a reuniting thereof by reason of the relatively small or minute receiving or selecting tubes merging step by step or by graduations into larger tubular elements of the sound conveyor, it should be understood that this expression is employed merely as an exponent of an arbitrarily selected theory of the operation, of which the true principle is at present in doubt but of which the result is a known fact.

Another theory of operation, of which there may be several, is that the sound waves associated with and due to "noises," as distinguished from tones produced by vibrating strings or columns of air as in pipes (flutes) and the equivalent thereof, are abrupt, irregular, non-continuous—instead of being uniform and regular and producing a train of harmonic sound waves having a well defined wave length or frequency and amplitude, to which the volume or capacity of the receiving chamber may be more or less accurately tuned as a means of prolonging and conserving those harmonic sounds which are being transmitted. Under this theory the minute receiving or selecting tubes are adapted to take up and respond to tinied, regular or sustained sound waves whereas they would reject the irregular or abrupt vibrations due to discordant sounds or noises. And, even though vibrations of the undesirable quality should to some extent penetrate the sound conveyor or transmitting passage their irregular character would be insufficient to carry throughout the length thereof or set up a sympathetic or responsive vibration throughout the extent of the conveyor, which obviously may be dimensioned, lineally and otherwise, to perpetuate only those waves or vibrations which are of the continuous, rhythmical and hence enduring quality peculiar to musical sounds. Presumably there is produced in the selecting tubes a backward reflection which interposes an interference to the transmission of the abrupt vibrations resulting from discordant sounds.

Still another theory of operation is based upon the presumption that the column of air or like fluid responsive to sound waves and which is represented in the structure herein disclosed by the laterally or transversely confined and lineally extended body of air contained in the conveyor leading from and communicating with the receiving chamber will be affected by regular sound waves or sustained or continuous sound waves of musical or tone characteristics admitted through a transmitting terminal of said conveyor even if the terminal is reduced in area or is subdivided to provide a multiplicity of minute branches or leaders arranged in con-

fluent contributory relation with the main column, whereas the more abrupt and irregular waves incident to discordant sound or noises and which are devoid of the continuity and uniformity of frequency and amplitude of the musical sounds or tones will be rejected,—or that if the waves incident to such discordant sounds or noises should penetrate the relatively minute subdivisions of the transmitting terminal of the conveyor, their progress will be impeded thereby and will be lost before reaching a point serving to interfere with the reading of the message at the receiving end of the conveyor. This theory is common to those previously suggested, however, in its recognition of the fact that regular or harmonic sound waves or those which are incident to definite tones are of practically uniform frequency and amplitude and operate or occur in the form of trains of sound waves and therefore are capable of a continued progress through even a restricted passage in alignment with their paths of pulsation, to the exclusion relatively of those vibrations which are lacking in these progressive and continuing characteristics.

Having fully described my invention what I claim as new and desire to receive by Letters Patent is:—

1. A tone clarifying instrument including a sound receiving chamber, tubes for breaking up sound waves, and a sound transmitting chamber for reuniting the sound waves in a clarified condition.

2. A tone clarifying instrument including a speaking tube, a sound receiving chamber with which said tube communicates, relatively small tubes communicating with the sound receiving chamber for breaking up sound waves, a sound transmitting chamber with which said small tubes communicate and in which the waves are reunited, and a receiving tube communicating with the sound transmitting chamber.

3. An interference eliminator including a sound receiving chamber, a loud-speaker communicating with said chamber, tubes communicating with said chamber for breaking up sound waves, and a sound transmitting chamber receiving and reuniting the sound waves after passage through the said tubes.

4. An interference eliminator including a sound receiving chamber, tubes communicating therewith, and means for adjusting the size of said chamber for varying pitch.

5. An interference eliminator including a sound receiving chamber, tubes communicating therewith, and means for moving said tubes to adjust the size of said chamber for varying pitch.

6. An interference eliminator including a sound receiving chamber, a speaking tube and a loud-speaker communicating there-

- with, and means for breaking up and reuniting, sound waves received in said chamber.
7. An interference eliminator including a sound receiving chamber, a speaking tube communicating therewith, tubes for breaking up sound waves, a sound transmitting chamber communicating with said tubes, and a receiver tube communicating with said sound transmitting chamber.
8. An instrument for clarifying audible messages having a chamber of variable capacity, and a tubular conveyor communicating with said chamber and of a linear extent capable of responding throughout its length to sound waves of sustained characteristics.
9. A tone clarifying instrument for use in the transmission of audible messages in the presence of disturbing and ear distracting sounds, consisting of a drum having a chamber tunable to respond to wave lengths at a selected pitch and a conveyor tube for receiving and conducting the responsive vibrations from said chamber.
10. A tone clarifying instrument for use in the transmission of audible messages in the presence of disturbing and ear distracting sounds, consisting of a drum having a resonating chamber tunable to respond to wave lengths at a selected pitch and a conveyor tube for receiving and conducting the responsive vibrations from said chamber.
11. A tone clarifying instrument for use in the transmission of messages in the presence of disturbing and ear distracting sounds, consisting of a drum having a reverberatory chamber tunable to respond to wave lengths at a selected pitch and a conveyor tube for receiving and conducting the responsive vibrations from said chamber.
12. A tone clarifying instrument for use in the transmission of messages in the presence of disturbing and ear distracting sounds, consisting of a drum having a chamber tunable to respond to wave lengths at a selected pitch and a conveyor tube for receiving and conducting the responsive vibrations from said chamber and having its entrance terminal in prolongation of said chamber.
13. A tone clarifying instrument for use in the transmission of messages in the presence of disturbing and ear distracting sounds, consisting of a drum having a chamber tunable to respond to wave lengths at a selected pitch and a conveyor tube for receiving and conducting the responsive vibrations from said chamber and having a subdivided entrance terminal.
14. A tone clarifying instrument for use in the transmission of messages in the presence of disturbing and ear distracting sounds, consisting of a drum having a chamber tunable to respond to wave lengths at a selected pitch and a conveyor tube for receiving and conducting the responsive vibrations from said chamber and having a subdivided entrance terminal.
15. A drum or housing having a chamber adapted to be tuned to the pitch of the selected tone—or length of the selected sound waves, and an extended conveyor tube communicating with said chamber and exteriorly protected by the housing.
16. An apparatus for selectively distinguishing the tones of a transmitted message from contemporaneous unrelated sounds, having a transversely confined column of fluid responsive to sound waves and provided at its receiving terminal with subdivisional confluent elements arranged in contributary relation with the body portion of the column.
17. An apparatus for selectively distinguishing the tones of a transmitted message from contemporaneous unrelated sounds, having a transversely confined column of fluid responsive to sound waves and provided at its receiving terminal with subdivisional confluent elements arranged in contributary relation with the body portion of the column and communicating therewith through successive partial or graduated groupings of the elements.
18. An apparatus for selectively distinguishing the tones of a transmitted message from contemporaneous unrelated sounds, having a transversely confined lineally extended column of fluid responsive to sound waves and having a relatively reduced transmitting terminal.
19. An apparatus for selectively distinguishing the tones of a transmitted message from contemporaneous unrelated sounds, having a transversely confined lineally extended column of fluid responsive to sound waves and having a relatively reduced and minutely subdivided receiving terminal.
20. An instrument for selectively distinguishing the tones of a transmitted message from contemporaneous unrelated sounds having a sound transmitting passage and a sub-dividing diaphragm intercepting the same, the passage having graduated condensing means in rear of the plane of the diaphragm.
21. An instrument for selectively distinguishing the tones of a transmitted message from contemporaneous unrelated sounds having a sound transmitting passage and a sub-dividing diaphragm intercepting the same, the passage being provided at opposite sides of the plane of the diaphragm respectively with expanding and condensing means.
22. A sound conveyor comprising a receiving chamber for sound waves, means for

1,593,779

abruptly breaking up said waves and means for progressively reuniting said waves.

23. An instrument for use in a conveyor of audible messages having means for intercepting discordant and unrelated sounds and including a subdividing medium and progressively confluent assembling passages.

24. An instrument for use in a conveyor

of audible messages having means for intercepting discordant and unrelated sounds and including a minutely perforated diaphragm disposed transversely in the path of sound waves and graduated assembling passages for receiving the sound waves from the plane of the diaphragm.

WILLIAM JAMES SCOTT.
